UNITED STATES PATENT OFFICE.

WALTER WEIMER, OF CHICAGO, ILLINOIS.

DESIGN FOR A CONDIMENTS-HOLDER.

SPECIFICATION forming part of Design No. 22,623, dated July 18, 1893.

Application filed June 16, 1893. Serial No. 477,885. Term of patent 7 years.

To all whom it may concern:

Be it known that I, WALTER WEIMER, a citizen of the United States, residing at Chicago, in the county of Cook and State of Illinois, have invented a new and original Design for Rotary Condiment-Holders, of which the following is a specification.

The invention relates to a new and original design for rotary condiment holders.

10 The object of the present invention is to provide an ornamental and attractive design for condiment holders; and the essential feature resides in a condiment holder composed of a circular base, a stem provided at its upper 15 end with an ornamental handle or top, an upper circular cruet support or holder, and a lower circular support having tapering radial division flanges and provided with a depending circumferential flange having handles.

20 The figure of the drawing is a perspective view of a rotary condiment holder showing my new design.

Referring to the drawing, 1 designates a circular base and 2 designates a central vertical 25 stem provided at its upper end with an ornamental top or handle 3 composed of oppositely disposed V-shaped portions 4 and 5, and

curved intermediate portions 6. Near the top of the stem is arranged a circular cruet holder 7 provided with a depending circumferential flange 8; and at the lower end of the stem above the circular base 1 is arranged a circular support 9, which is provided with a depending circumferential flange 10 having horizontally disposed handles 11. On the upper face of the circular support 9 are arranged radial division flanges 12, which are vertically disposed, and which have their upper edges inclining downward from the center of the support 9. The radial flanges 12 form sector-shaped spaces or compartments 13.

It will be apparent that the rotary condiment holder presents an ornamental and attractive appearance.

What I claim is—

25 The design for condiment holders herein shown and described.

In testimony that I claim the foregoing as my own I have hereto affixed my signature in the presence of two witnesses.

WALTER WEIMER.
